UNITED STATES PATENT OFFICE.

CLIFFORD COATES HAMILTON AND JOSEPH HUTCHINSON, OF GULL LAKE, SASKATCHEWAN, CANADA.

GREASE CUP.

Application filed March 22, 1922. Serial No. 545,719.

To all whom it may concern:

Be it known that we, CLIFFORD C. HAMILTON and JOSEPH HUTCHINSON, subjects of the King of England, and residents of Gull Lake, in the Province of Saskatchewan and Dominion of Canada, have invented certain new and useful Improvements in Grease Cups, of which the following is a specification.

10 Our invention relates generally to grease cups, more particularly to grease cups of the type of construction disclosed in Letters Patent of the United States No. 1,336,135, granted to us on April 6, 1920, and it consists in 15 the combinations, constructions and arrangements herein described and claimed.

An object of our invention is to provide a grease cup of the character described having means for releasably maintaining the 20 detachably connected parts thereof in assembled position without in any way rendering the assembly of such parts more difficult of accomplishment than would be the case where a grease cup of ordinary construction is used.

A further object of our invention is to provide a grease cup of the character described in which a body portion carries a spring member adapted to engage a detachable cap for the body portion in such manner as to tend to hold the cap in applied position upon the body portion and to prevent retrograde movement of the cap relatively to the body portion on account of vibrations communicated to the grease cup in service.

A further object of our invention is to provide a grease cup having means for guarding the inlet end of the delivery or discharge portion thereof to prevent the passage into such discharge portion of solids or semi-solid masses of grease or any other material which would obstruct the delivery and prevent the feeding of a viscous lubricant therethrough continuously in the usual manner.

A further object of our invention is to provide a grease cup of the character described, which is of simple construction, not 50 likely to get out of order easily, and thoroughly practical commercially.

Other objects and advantages will be apparent from the following description, and the novel features of the invention will be

particularly outlined in the appended claims. 55

Our invention is illustrated in the accompanying drawing, forming a part of this application, in which—

Figure 1 is a side elevation showing a bearing equipped with our improved grease 60 cup.

Figure 2 is a vertical section through the improved grease cup, and

Figure 3 is a perspective view showing the parts of the grease cup in detached or 65 separated positions.

In carrying our invention into effect in the form now preferred by us, as illustrated in the accompanying drawings, we provide a body consisting of a substantially funnel-shaped lower portion 1 formed integrally with a cylindrical upper portion 2. The body is made of any suitable material, such as any one of the metals ordinarily used in the manufacture of like devices and the funnel-shaped portion 1 and the cylindrical portion 2 thereof are preferably formed integrally with each other. The walls of the funnel-shaped portion 1 are merged at the lower end of the body into the walls of a 70 tubular stem 3 which is preferably formed with the upper part thereof polygonal in contour, as indicated at 4 in Figures 1 and 3, with the lower part thereof reduced diametrically and screw threaded externally adjacent to the end thereof, as indicated at 5. The stem 3 is shown as being aligned with the body and is provided at its lower end 75 with a discharge orifice 6.

The cylindrical portion 2 is provided with 80 external screw threads 7 adapted to engage screw threads 8 formed on the inner wall of a cap 9, whereby the latter will be detachably secured to the body.

It is desirable that the cap be held against 95 accidental displacement from the body and particularly against a retrograde movement, such as would likely be occasioned by vibrations communicated to the device in service. It is also desirable that the means for preventing accidental displacement of the cap should be of such nature as not to preclude ease of assembly of the body and the cap. To this end, we provide a flat spring member 10 which we arrange substantially in 100 diametrical position within the body. It is to be observed that the spring member 10 is formed intermediately to provide an arched

or substantially U-shaped guard portion 11 which is arranged to overlie the inlet end of the stem 3. The portions of the spring member 10 extending oppositely from the 5 arched intermediate portion are adapted to lie flatwise upon the inner wall of the funnel-shaped portion 1 and are bent upwardly at 12 adjacent to the juncture of the funnel-shaped portion 1 with the cylindrical portion 2 to extend vertically in spaced parallel 10 relation to the inner wall of the latter, as indicated at 13—13 to the plane of the upper edge of the cylindrical portion 2. The portions 13—13 are then bent substantially 15 at right angles to extend oppositely substantially in the plane of the upper edge of the cylindrical portion 2 as indicated at 14—14. The portions 14—14 terminate with the ends thereof projecting slightly beyond 20 the screw threads 7 and being curved to conform with the curvature of the screw threaded cylindrical portion 2, as shown at 25 15—15. Rivets 16 or like fastening means projected through the walls of the inclined or funnel-shaped portion 1 and through the 30 portions of the spring member 10 disposed thereupon secure the spring member 10 to the body in the position in which illustrated in the drawings. It is to be observed that 35 the rivets 16 engage the spring member 10 at points between the upwardly bent portions 13—13 and the arched intermediate portion 11, whereby the end portions of the spring member 10 are capable of limited movement under stress or under actuation 40 occasioned by their inherent spring qualities, while the arched intermediate portion 11 is held substantially rigid.

The convolution of the screw threads 8 at 45 the lower end of the cap is cut away to provide a counter-bore 17 adapted to receive the ends of the spring member 10, the curved end walls 15—15 of the spring member 10 being guided by their engagement with the 50 walls of the counterbore 17 into engagement with the screw threads 8 as the cap is screwed on the cylindrical portion 2 of the body.

From the foregoing description of the 55 various parts of the device, the operation thereof may be readily understood. The embodiment of the invention illustrated is adapted to contain a lubricant which is sufficiently fluid to be fed continuously through the discharge orifice 6 to a bearing, such as indicated at 18, to which the stem 3 is connected through the agency of the screw threads 5. When the cap 9 has been placed in applied position upon the body in the 60 manner described, the end portions 14—14 of the spring 10 will be continuously urged against the screw threads 8 of the cap, thereby yieldingly resisting movement of the latter relatively to the body and preventing 65 displacement of the cap from the body on

account of vibrations caused by shocks or jars incident to service. The counter-bore 17 permits the entrance of the ends of the spring within the cap and guides the ends into engagement with the screw threads 8. 70 The arched portion 11 overlies the open upper end of the bore of the stem 3 and prevents the passage thereinto of any large solid objects or hardened masses which would be likely to obstruct the bore of the 75 stem. The arched portion 11 does not in any way interfere with the passage of a viscous lubricant from the body of the device into the stem.

Obviously, our invention is susceptible of 80 embodiment in forms other than that illustrated in the accompanying drawing, and we therefore consider as our own all modifications and adaptations of the form of the device disclosed herein which properly fall 85 within the scope of the appended claims.

We claim:—

1. A grease cup comprising a hollow body portion open at its upper end and provided at its lower end with an outlet, a cap removably secured upon the body portion, and a spring disposed substantially diametrically of the body and having the ends thereof reacting against the walls of the cap to tend to hold the latter against movement 95 relatively to the body, the intermediate portion of the spring being disposed in overlying spaced relation to the outlet.

2. A grease cup comprising a body adapted at its upper end to receive a lubricant and 100 being provided with external screw threads adjacent to its upper end, said body having an outlet opening through the lower end thereof, a cap provided with screw threads internally adapted to engage the screw 105 threads of the body, and a spring member secured to the inner walls of the body to extend transversely thereof and being of such length that the ends thereof extend slightly beyond the screw threads of the 110 body and are adapted to react against the screw threads of the cap when the latter is in applied position upon the body, said spring member having the intermediate portion thereof arched to lie in overlying 115 spaced relation to the outlet.

3. A grease cup comprising a hollow body having a tapering lower portion provided with a central outlet, a cap removably secured upon the body, and a spring member 120 disposed transversely of the body, said spring member having an arched intermediate portion overlying the outlet orifice and spaced therefrom, portions extending oppositely from the arched portion and being secured to 125 the body at points intermediate of the arched portion and the ends of the spring member, and end portions extending normally beyond the outer wall of the body substantially at diametrically opposite points and 130

reacting against the inner wall of the cap to hold the latter against accidental displacement from the body.

4. A grease cup comprising a body adapted to receive a lubricant, a cap removably mounted upon the body and being provided with a counter-bore at its lower end, and a spring member disposed transversely of the body and having the outer ends thereof extending slightly beyond the outer wall of the body at the upper end thereof, the normal distance between the ends of said spring member being substantially equal to the diameter of the counter-bore, whereby the ends of the spring member will enter the counter-bore and be guided by their engagement with the wall of the latter into engagement with the inner wall of the cap above the counter-bore when the cap is placed upon the body.

5. A grease cup comprising a body adapted to receive a lubricant, a cap adapted to be detachably mounted upon the body and being provided with a counter-bore at its

lower end, a spring member disposed transversely of the body and having the ends thereof extending slightly beyond the outer wall of the body, the distance between the ends of said spring member being substantially equal to the diameter of the counter-bore, and said spring member being curved at its ends to conform with the curvature of the wall of the counter-bore.

6. A grease cup comprising a body adapted to receive a lubricant and being screw threaded externally at its upper end, a cap screw threaded internally adjacent to its lower end for engagement with the screw threads of the body, the lowermost convolution of the screw threads being cut away to provide a counter-bore at the lower end of the cap, and a spring member disposed substantially transversely of the body with the ends thereof extending slightly beyond the outer wall of the body and being adapted to enter the counter-bore of the cap.
